UNITED STATES PATENT OFFICE.

EDWIN RUTHVEN WHITNEY, OF MANCHESTER, NEW HAMPSHIRE, ASSIGNOR
TO THE STANDARD ELECTRIC COMPANY OF VERMONT, OF ST. JOHNS-
BURY, VERMONT.

COIN-OPERATED ELECTRICAL WEIGHING-SCALE.

SPECIFICATION forming part of Letters Patent No. 371,869, dated October 18, 1887.

Application filed March 22, 1887. Serial No. 231,996. (No model.)

To all whom it may concern:

Be it known that I, EDWIN RUTHVEN WHITNEY, of Manchester, in the county of Hillsborough and State of New Hampshire, have 5 invented certain new and useful Improvements in Weighing-Machines; and I do hereby declare that the following is a full, clear, and exact description of the same.

The invention relates to that class of weighing-machines which are inoperative until by 10 the introduction of the coin required the mechanism is released and enabled either to perform the operation or indicate the result, and has special reference to those machines in 15 which the weight of the coin will put in circuit an electro-magnet the armature of which acts through suitable means to cause the needle to register the weight.

The invention consists in the combination, 20 with the weighing mechanism proper—viz., that actuated by the pressure on the platform of the person to be weighed—of an electrical registering device normally disconnected from the weighing mechanism proper, but connected 25 therewith so as to be operated thereby by the introduction of the proper coin.

It also comprises certain improvements in the construction of the coin-receptacle and conduits through which said coin passes.

30 The special mechanism above referred to may be thus briefly described: The needle or pointer is secured on the end of a sleeve having formed on its inner end a disk, the whole being mounted loosely on the spindle proper, 35 which is connected with the actuating-rod of the weighing apparatus by a lever or arm. On this spindle is mounted rigidly a disk in close proximity to the disk on the sleeve, and also in the same way an electro-magnet having on its frame a projection, to which is pivoted a curved lever having formed on one end a shoe and on the other a fork engaging with a clutch-armature moving freely on the spindle. When the coin is dropped into the proper 40 receptacle, it acts, through levers and a cup with mercury in it, to put the magnet into electrical circuit. The magnet will draw on the clutch-armature, and thus operate the curved lever so as to grip both the fixed and 45 loose disks, thus imparting through these to

the pointer the movement derived from the weighing mechanism. The first section of the conduit is connected with the weighing mechanism, so that if the person steps onto the platform before inserting the coin through the 55 casing this section of the conduit will be by his action drawn down, so that the coin will fall into the case and accomplish nothing. The introduction of too small a coin will also fail to operate the mechanism.

The case in which the mechanism is contained has the front, front and back, or all four sides, mainly composed of glass, so that every detail of its construction and operation can be viewed.

55 For full comprehension of the invention reference must be had to the annexed drawings, forming part of this specification, in which—

Figure 1 is a front view of the machine with 70 the front removed; Fig. 2, a vertical section on line xx , Fig. 1, looking in direction indicated; Fig. 3, a horizontal section on line zz , Fig. 1, looking down, with part of weighing mechanism shown, (the glass front being shown 75 in place in Figs. 2 and 3;); Fig. 4, a detail side view of parts carried on the needle-spindle, and Fig. 5 a section of the coin-sorter.

Similar letters of reference indicate like 80 parts.

A is the ordinary platform, any depression of which is transmitted through a connecting-rod, A', and the well-known system and combination of scale-levers shown in Fig. 1 (consisting of knife-edged standards a and a' , 85 frame a^2 , carrying shot-cup or weight a^3 , the two levers a^4 a^5 , and equalizing-spring a^6) to the rod A ^{2} , from which it is taken up by the weighted lever A ^{3} , which is secured rigidly to the needle-spindle B, as shown, carried in 90 the casing and in any suitable bearing, B', and these connections cause the said spindle to revolve an amount proportional to that of the depression of the platform.

95 On the spindle B is mounted loosely a sleeve, C, Figs. 2, 3, and 4, having formed on its inner end a disk, C', and on its outer end a flange, C ^{2} , to which is secured the needle or pointer D, of well-known and suitable form.

100 E is a disk of the same diameter as C', and

mounted rigidly on the spindle B in close proximity to it.

F is an electro-magnet placed in circuit, as will be presently described, and having formed 5 on it a projection, F', Figs. 2 and 4, to which the curved lever G is pivoted, said lever terminating at one end in a shoe, G', and at the other in a fork, G'', of ordinary form, engaging in the clutch-armature H, moving freely 10 on the spindle B.

I is a bar placed horizontally where shown in the drawings, carried on knife-edges i i in the brackets J J, secured to the casing. In the bent ends I' I' of this bar are formed seats, 15 in which rest the knife-edge supports k k of the main conduit or runway K, formed of a frame carrying the ends of any suitable number of zigzag inclined troughs, K' K', down which the coin passes from the conduit, which 20 it enters when inserted in the case, into any suitable hopper, S, and receptacle S'.

The knife-edges i i of the bar I act as fulcrum-points for it, the weights I' on the arm I' being an equipoise for the weight of the 25 runway K.

L is a bell-crank lever pivoted to the casing of the machine and having a projection, L', acted upon by the insulated arm I', secured to the bar I.

30 l is a rod attached to L, which, when the other end of the lever is raised, will dip into the mercury contained in the cup M, carried on a fixed bracket.

N is a suitable battery carried in the bottom 35 of the case, one pole being connected by line O to the mercury-cup M or its bracket and the other by line O' to electro-magnet F, a third wire, O'', connecting the magnet with the bell crank lever L, (in electrical connection 40 with rod l.)

Figs. 2 and 5 show the coin-sorter P, of some such shape as that shown, and secured to the top casing, Y, of the machine, in which are formed openings y' y'.

45 P' is the runway proper of the coin-sorter, of such a section that a coin smaller in diameter than the one designated will fall out of it before reaching the outlet y', and into the lower space in the casing P, and thence pass through 50 the opening y' into the funnel Q, which will deliver it into the receptacle S' through hopper S. The funnel Q is shown in Fig. 1, and is positioned so as to reach under the entire sorter P. Access may be had to the interior 55 of P through the door P' to clear the runway should it in any way become blocked.

R is an inclined trough secured to the casing, the end section, R', of which (into which the coin drops through the slot y') is hinged 60 thereto and connected by rod a' with any part of the weighing mechanism, so as to move with it. By this arrangement of the hinged section and connection the coin, instead of passing through the runway and causing the 65 devices to operate, will be discharged directly into the funnel, when in any case the body to

be weighed is placed upon the platform before the coin is inserted.

Z is the front frame, as shown in Figs. 2 and 3, and Z' the glass face of same.

The operation of my invention is as follows: Before mounting the platform the person to be weighed inserts into P the proper coin, which passes down the runway P', through the opening y' into the trough R, and thence 75 into the conduit proper, K. As soon as the coin enters this conduit the equipoise of the bar I is disturbed, and the insulated end of the arm I', acting against the projection L' of the bell-crank lever L, will cause the rod l to dip 80 into the mercury contained in the cup M, and thus complete the electrical circuit from the battery N through the electro-magnet F. The result of this movement is that the magnet, being charged, draws on the clutch-armature H, 85 so as to bring the shoe G' down on the peripheries of the disks C' and E. This action has the effect of connecting the disk C', its sleeve C, and pointer D with the shaft B through the rigid disk E, and causing the said disk C', 90 sleeve and pointer D to move in unison with the shaft. As heretofore explained, the shaft is in connection, through the ordinary rods, levers, &c., with the platform, and it will thus be seen that the movement of the platform 95 will be transmitted through the shaft, disks, and sleeve to the pointer, which will indicate the weight of the body upon the platform. The connection of the registering mechanism with the weighing mechanism just referred to 100 will last so long as the coin is passing down through the several zigzag troughs K' K', during which time the person wishing to weigh himself can do so and have the result indicated. So soon as the coin passes out from 105 the lowermost of the troughs K' K' into the receptacle S the equipoise of the bar I is restored and the rod l withdrawn from the mercury-cup M, so as to break the electrical circuit and allow the parts to resume their normal position. A smaller coin than the one required will simply fall out of the runway P and through y' into the funnel Q (shown in dotted lines, Fig. 2) without actuating the mechanism. A similar result will follow should 110 the weighing mechanism be drawn before the coin is introduced, as in that case the hinged portion R' of the trough R will be drawn down by the weighing mechanism and allow the coin to roll into the funnel Q.

115 Although I prefer to use as weighing mechanism the system of levers, &c., shown in the drawings, it must be understood that I do not confine myself to this, as my invention may be used in combination with several other 120 styles of construction.

I am aware that the combination of a movable coin-tube with mechanism adapted to be operated thereby, and also with an electrical circuit adapted to be closed by the introduction 125 of a coin and operate other devices arranged to operate entirely independent of the first

mechanism, is not new, and I do not claim such combination, broadly.

What I claim is as follows:

1. In a weighing-machine, and in combination, the registering device, the weighing mechanism normally out of connection with the said registering device and adapted while in connection to impart movement to said registering device when it is itself operated, a conduit for the coin, and an electrical device to throw the two sets of devices into dependent and co-operative engagement, said electrical device being adapted to be energized while the coin is in the conduit, substantially as described.

2. In a weighing-machine, and in combination, the registering device, the weighing mechanism normally out of connection with the said registering device and adapted while in connection to impart movement to said registering device, a movable conduit for the coin, and means, substantially as described, to be actuated while the conduit is in its moved position for throwing the two sets of devices into operative engagement, substantially as described.

3. In a weighing-machine, and in combination, the weighing mechanism proper, the indicating device, an electric circuit, an electro-magnet, means, substantially as described, adapted to be operated by said magnet to form a connection between the indicating device and the weighing mechanism, a movable runway arranged to be operated by the weight of a coin, and means operated by said runway to close the electrical circuit, substantially as described.

4. In a weighing-machine, and in combination, the weighing mechanism, the indicating device, the electrical circuit, the electro-magnet, means, substantially as described, operated by said magnet to form a connection between the said weighing and indicating devices, a runway having slight movement upon the introduction of the coin, a mercury-cup, as M, and a lever operated by the runway for establishing the circuit, substantially as described.

5. In a weighing-machine, and in combina-

tion, the weighing mechanism, the shaft B, 50 connected to said weighing mechanism, the indicating device loose on said shaft, the electric circuit, the electro-magnet, and means, substantially as described, for fixing said indicating device to the shaft upon the establishment of said circuit, the movable runway, and means operated thereby to establish the circuit, substantially as described.

6. In a weighing machine, and in combination, the weighing mechanism, the indicating 60 device normally out of connection with the weighing mechanism, the runway, and means for establishing a connection between the indicating and the weighing mechanism, said runway having a hinged section connected 65 with the weighing mechanism to be operated thereby, substantially as described.

7. The coin-sorter P, having a runway, P', for the coin, said runway having an open bottom and flanges for directing a coin of proper 7c size, and the door P', substantially as described.

8. In combination, the weighing and indicating devices normally out of connection one with the other, means for forming a connection between the two, a movable runway adapted to actuate the said connecting means while in its moved position, said movable runway being zigzag in form, whereby the connection between the weighing and indicating 80 devices is of sufficiently long duration to effect the desired indication, substantially as described.

9. In combination, the weighing and indicating devices normally out of connection one 85 with the other, means, substantially as described, for forming a connection between them, a movable runway adapted to operate by the weight of the coin and act upon said connecting means, and a stationary section at the 90 beginning of the runway, said section having a hinged portion, R', connected with the weighing mechanism, substantially as described.
